UNITED STATES PATENT OFFICE.

JOHN CAMPBELL, OF MINNEAPOLIS, MINNESOTA, ASSIGNOR OF FIFTY-ONE ONE-HUNDREDTHS TO THOMAS E. McDERMOTT, OF MINNEAPOLIS, MINNESOTA.

OAR-LOCK.

1,026,654.

Specification of Letters Patent.

Patented May 21, 1912.

Application filed May 12, 1910. Serial No. 560,939.

To all whom it may concern:

Be it known that I, JOHN CAMPBELL, a citizen of the United States, residing at Minneapolis, in the county of Hennepin and 5 State of Minnesota, have invented a new and useful Oar-Lock, of which the following is a specification.

This invention relates to oarlocks and its object is to provide a simple and compact 10 device of this character which is cheap to manufacture and to which an oar can be readily attached.

Another object is to provide an oarlock which does not interfere with any of the 15 necessary movements of an oar and permits the oar to be readily feathered.

A further object is to provide an oarlock which securely holds the oar under all conditions, thus preventing its loss when 20 released.

With these and other objects in view the invention consists of certain novel details of construction and combinations of parts hereinafter more fully described and pointed out 25 in the claim.

In the accompanying drawings the preferred form of the invention has been shown.

In said drawings:—Figure 1 is a view partly in section and partly in elevation of 30 an oar lock constructed in accordance with the present invention, the oar being shown in section within the oarlock. Fig. 2 is a section on line A—B Fig. 1. Fig. 3 is a section on line C—D Fig. 1, the oar being 35 shown in elevation. Fig. 4 is a view partly in section and partly in elevation showing a modified construction.

Referring to the figures by characters of reference 1 designates a shank having an 40 annular shoulder 2 adapted to limit the downward movement of the shank in the socket provided therefor and extending from the upper portion of the shank is a yoke 3 having a trunnion 4 extending inwardly 45 from the free end thereof and directly opposite a locking pin 5 which is slidably mounted in the upper end portion of the shank 1 and is connected to a spring strip 6 attached to the shank. This strip serves 50 to hold the pin 5 normally projected beyond the shank 1 and toward the trunnion 4, the said pin thus serving as a movable bearing for a ring 7. Said ring has recesses 8 55 therein at diametrically opposed points, one of the recesses being adapted to receive the

trunnion 4 while the pin 5 is adapted to project into the other recess.

The oar, which has been indicated at 9, has plates 10 secured to opposite portions thereof, each plate being provided with outstanding ears 11 arranged in pairs and spaced apart a distance slightly greater than the width of the ring 7. These plates are adapted to be secured to the oar in any suitable manner and are preferably bowed 60 transversely so as to fit snugly upon said oar. 65

In assembling the parts the plates 10 are first placed within the ring 7 and with said ring seated between the ears 11. The oar 9 is then inserted between the plates 10 and 70 said plates are fastened to it. It will be apparent therefore that the oar can be rotated within the ring but the ears 11 will prevent it from becoming displaced longitudinally relative thereto. After the oar 75 has thus been mounted within the ring, said ring may be placed in position within the yoke 3 by placing the trunnion 4 in one of the notches 8 and then pressing the surface of the ring against the movable pin 5 until 80 said pin is brought to a position in register with the opposed recess 8 whereupon the pin will move into the recess and thus lock the ring in position. After the shank 1 has been placed in its socket, the oar can, obviously, be operated in the usual manner and, 85 by reason of the fact that the oar can be rotated within the ring 7, it will be apparent that there will be no difficulty in feathering the oar. Should the oar be released, 90 the ears 11, by engaging the ring 7, will prevent it from slipping out of the boat. When it is desired to ship the oar by detaching it from the oarlock, it is merely necessary to pull outwardly on the spring 6 so 95 as to withdraw the pin 5 from the adjoining recess 8. The said ring can then be slipped off of the trunnion 4 and thus removed from the yoke.

Instead of utilizing a pin 5 and spring 6 100 such as shown in Fig. 1, a screw 12 may be mounted within the shank 1, there being a thumb lever 13 or the like at one end of the screw while the other end of said screw is reduced in diameter and adapted to project into a socket in the ring 7. By turning the screw in one direction it can be disengaged from the ring and by turning it into the opposite direction it can be forced into the socket so as to secure the ring in place. 110

It is of course to be understood that various changes may be made in the construction and arrangement of the parts without departing from the spirit or sacrificing any 5 of the advantages of the invention as defined in the appended claim.

What is claimed is:—

An oarlock including a yoke, a trunnion fixed relative thereto, a movable trunnion 10 alining with the fixed trunnion, the two trunnions being oppositely disposed within the yoke, a spring for holding the movable trunnion normally projected into the yoke, a one-pieced continuous ring having diametrically opposed recesses for the reception 15

of the trunnions, oppositely disposed plates for attachment to an oar, and spaced projections upon each plate for slidably engaging the ring, said plates being disposed within said ring and constituting means for holding an oar against longitudinal movement within the ring. 20

In testimony that I claim the foregoing as my own, I have hereto affixed my signature in the presence of two witnesses. 25

JOHN CAMPBELL.
